Primary Examiner — Susan Bennett Hattan*Assistant Examiner* — Marie D. Fast Horse(74) *Attorney, Agent, or Firm* — Lewis Roca Rothgerber
Christie LLP(57) **CLAIM**

The ornamental design for spoke segment of a vehicle wheel, shown and described.

DESCRIPTIONFIG. 1 is a perspective view of a spoke segment of a vehicle wheel according to my new design;
FIG. 2 is a elevational view thereof;

FIG. 3 is a perspective view of a second embodiment of a spoke segment of a vehicle wheel according to my new design;

FIG. 4 is an elevational view of the second embodiment;
FIG. 5 is a perspective view of a third embodiment of a spoke segment of a vehicle wheel according to my new design; and,FIG. 6 is an elevational view of the third embodiment.
The broken lines consisting of long and short dashes depict the boundary of the claim, which extends to the boundary but does not include the boundary.**1 Claim, 6 Drawing Sheets**(56)
